UNITED STATES PATENT OFFICE

OTTO H. HARTMANN, OF CASSEL-WILHELMSHOHE, GERMANY, ASSIGNOR TO SCHMIDT'SCHE HEISSDAMPF-G. M. B. H., OF CASSEL-WILHELMSHOHE, GERMANY, A CORPORATION OF GERMANY

BOILER GENERATING STEAM ACCORDING TO THE INDIRECT METHOD

Application filed January 24, 1928, Serial No. 249,120, and in Germany March 17, 1927.

My invention relates to boilers generating high-pressure steam according to the indirect method and is designed in particular for those cases in which a boiler installation requires a number of units, in order either to provide an ample reserve or to meet widely differing demands at different times.

In boiler installations with boiler units of the usual kind (for example, those with steeply-inclined or slightly-inclined tubes generating steam according to the direct method), a complete set of steam drums with their appropriate fittings usually corresponds to each furnace of the battery. The efficiency of a boiler installation of this kind falls off, however, at low loads, as for example in the type of installation in which the demand for steam over long periods is only a small fraction of the average demand. In addition, if it is necessary to draw a fire in order to effect repairs to the tube system of the corresponding steam drum or set of steam drums, the entire heating surface associated with the drum or drums concerned, becomes inoperative as regards the generation of steam.

In contrast to the above, my present invention makes it possible to work boiler installations at a good efficiency for long periods of time at loads below the average; further, if it is necessary to effect repairs to the tube system, a smaller fraction of the heating surface becomes inoperative.

With the objects set forth, my invention consists in a boiler installation of the kind indicated in which the heat-absorbing parts of the tube system serving for the indirect generation of high-pressure steam and corresponding to an individual steam drum, are sub-divided into two or more sections separating from one another and arranged respectively in the combustion chambers of a corresponding number of independent furnaces.

In addition, the steam superheater and the preheater commonly provided for the circulating heat-carrier are likewise preferably sub-divided into sections corresponding with the number of independent furnaces.

Referring to the accompanying drawings which show one form of the invention by way of example:—

Figure 1 shows a section of a boiler installation comprising a number of units, while

Figure 2 shows in section on the line II—II of Figure 1 a part of one of the units.

In Figure 1, three drums, A, B and C, are shown in which the high-pressure working steam is generated according to the indirect method by means of tube systems, 1, 2, 3, lying in the water spaces of the drums and connected (by connections not shown in Figure 1) to tube systems, 4, 5 and 6, and 7, 8 and 9, which are arranged in the combustion chambers of the boilers.

The tube systems, 1 and 4 or 5, as well as 2 and 6 or 7, and so forth, form a number of closed circuits in which circulates the heat-carrying medium, for example water, to which heat from the hot gases is imparted by way of the elements, 4, 5, 6, 7, and so forth, while in the elements, 1, 2 and 3, the heat-carrying medium gives up its heat to the water in the steam drums, A, B and C.

Two furnaces are shown in association with each steam drum; thus, the furnaces, 10 and 11, correspond to the drum, A, the furnaces, 12 and 13, to drum, B, and the furnaces, 14 and 15, to drum, C. Each of these furnaces, 10, 11, 12, and so forth, is independent, that is, it can be brought into or out of operation without affecting the other furnaces. The drum, A, contains the heat-emitting parts of the tube systems which lie in the combustion chambers of the two furnaces, 10 and 11, and so on.

If, therefore, by way of example, only one-half the quantity of steam is required from a given unit over a certain period of working, one of the furnaces (10 for example) can be put out of operation while the other furnace (11) continues working. In this case only half of the heat-emitting elements, 1, in the drum, A, generate high-pressure steam, that is to say, only half as much steam is generated as at full load.

The circulation tubes passing through each particular furnace are so disposed with respect to the drum as to prevent a circulation therethrough when its respective furnace is not operating. As a consequence, the shutting down of one furnace will not be accom-

panied by a continuation of the flow of the circulating medium through the tubes in the cold furnace and a corresponding decrease in the efficiency of the unit.

5 Further, in the case of replacements or repairs, without interrupting the working of the installation as a whole, the operation of one furnace can be entirely stopped.

10 In contrast to the usual forms of boilers, the essential advantage of the present invention lies in the fact that a fraction of the normal quantity of steam can be generated without the efficiency of the installation suffering. In addition, due to the arrangement 15 of a single working steam drum for several independently-fired tube systems, fewer fittings and accessories are required and consequently the cost of production of the improved boiler installation is in general reduced.

20 A boiler installation according to the present invention is equally suitable for coal, oil or other fuel.

25 If desired, a superheater, 16, and a preheater, 17, can be arranged in the flue of each furnace (see Figure 2) and connected in the usual manner with the other parts of the boiler, such heaters being preferably subdivided into sections to correspond with the 30 number of independent furnaces.

Further, a by-pass, 18, with damper, 19, may be provided for regulating the temperature of the steam in the superheater, 16.

35 Instead of two independent furnaces, as shown, for each individual steam drum, three or more such furnaces may be provided as desired.

40 Having now particularly described and ascertained the nature of my said invention and in what manner the same is to be performed, I declare that what I claim is:—

45 1. A boiler installation, comprising in combination, a steam drum, a plurality of furnaces, a plurality of sets of tubes in said drum, and a set of tubes in each of said furnaces disposed below the said sets of tubes in the drum, each of said sets of furnace tubes being connected with an individual set of the tubes in the drum to form a closed 50 system therewith for a circulating heating medium, whereby said drum is adapted to be heated by a plurality of closed systems.

55 2. A boiler installation according to claim 1, having a superheater for the steam generated, and a preheater for the circulating medium, the said superheater and preheater being subdivided into sections corresponding to the number of separate furnaces.

60 In testimony whereof I affix my signature.
OTTO H. HARTMANN.
